United States Patent Office

Des. 179,854
Patented Mar. 12, 1957

179,854

MEMORIAL MARKER

John F. Livers, Kansas City, Mo., assignor to Holy Sepulchre Cemetery, Rensselaer, N. Y., a proprietorship

Application January 20, 1954, Serial No. 28,613

Term of patent 14 years

(Cl. D79—2)

I claim:

The ornamental design for a memorial marker, as shown.
